(57) **CLAIM**

The ornamental design for a display screen with an animated graphical user interface, as shown and described.

DESCRIPTION

FIG. 1 is a front view of a display screen with an animated graphical user interface showing a first image of sequence; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; and, FIG. 8 is an eighth image thereof.

The three outer-most broken line rectangles represent an electronic device in the FIGURES and are included for the purpose of illustrating environmental structure; the innermost broken line rectangle depicting a display screen as well as all other broken lines illustrating portions of the graphical user interface in the FIGURES are included for the purpose of illustrating portions of the article; all broken lines form no part of the claimed design. The appearance of the transitional image sequentially transitions between the images shown in FIGS. 1-8. The process or period in which one image transitions to another image forms no part of the claimed design.
